UNITED STATES PATENT OFFICE

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
LONDON, ENGLAND.

BREECH-LOADING ORDNANCE.

1,302,523.

Specification of Letters Patent.

Patented May 6, 1919.

Application filed April 15, 1915. Serial No. 21,623.

To all whom it may concern:

Be it known that we, Sir ARTHUR TREVOR DAWSON, knight, and GEORGE THOMAS BUCKHAM, both subjects of the King of Great Britain, residing at Vickers House, Broad-
way, Westminster, in the county of London, England, have invented certain new and useful Improvements in or Relating to Breech-Loading Ordnance, of which the following is a specification.

This invention relates to breech loading ordnance.

According to this invention the breech mechanism of the gun is inclosed by a cylindrical or other suitably shaped cover which is detachably held in place on the gun in a watertight manner by suitable means; for example by an angularly displaceable ring coöperating with a shoulder or flange on the gun. This ring may have projections which enter cam grooves formed in the periphery of the shoulder or flange, and may be rotatably connected to the cover.

It may be found difficult, especially if the cover has remained in position on the gun for some time, to unlock the ring merely by a handle provided for this purpose; we therefore provide means for exerting a powerful initial unlocking movement on the ring. These means may comprise a tangentially arranged screw threaded bolt or the like interposed between the ring and a projection on the gun and adapted to be actuated by a lever or other device for enabling the necessary power to be exerted thereon.

In order that the said invention may be clearly understood and readily carried into effect, we will describe the same more fully with reference to the accompanying drawings, in which:—

Figures 1 and 2 are respectively a rear elevation and a side elevation showing a constructional form of the watertight cover in position on the gun.

Fig. 3 is a section taken approximately on the line 1, 1 of Fig. 1, and

Fig. 4 is a view showing the formation of one of the cam grooves in the flange of the gun.

A is the breech end of the gun, A' the

breech actuating hand lever, and A² the aforesaid shoulder or flange on the gun. B represents the aforesaid cover, C represents the aforesaid ring and C' its operating handle. C², C², C² represent the projections on the ring and a², a², a² their coöperating cam grooves in the flange A².

In the example shown the rear face of the flange is formed with an annular rib or rounded projection a³ with which a packing ring c carried by the cover coöperates in order to form a watertight joint. The front portion of the cover fits over a cylindrical part a of the breech end of the gun.

The ring C is rotatably connected to the cover by means of screw threaded studs (one of which is indicated by the reference letter c' in Fig. 2) carried by the ring and engaging in a circumferential groove b formed in the cover.

When applying the cover to the breech mechanism the projections C² on the ring C are first passed through the open ends a^{2x} (Fig. 4) of the cam grooves a² and the ring 75 is then angularly displaced by its handle C' to cause the projection C² to enter the cam grooves a². The coöperation of these parts causes the packing ring c to be pressed forcibly against the rib or projection a³ and a watertight joint to be thereby made.

The handle C' is pivoted to a bracket C³ on the ring C and is held in its operative or radial position or in its inoperative or tangential position, by the engagement of a removable pin c² with one or other of two holes in the bracket. Fig. 1 shows by full lines the inoperative position and by chain lines the operative position of this handle. The chain line position of the bracket C³ is 90 that assumed by it when the ring C is unlocked.

D represents the aforesaid screw threaded bolt for enabling the initial unlocking movement of the ring C to be performed when necessary. This bolt is carried by the ring and coöperates with a projection or stop A^x (Fig. 1) on the gun so that by actuating this bolt the ring can be forcibly moved in the direction to unlock it.

The rear end of the cover B is provided with a hollow boss B' which has a transverse

bar *b'* serving as a hand grip to facilitate the placing of the cover in position and its removal.

What we claim and desire to secure by Letters Patent of the United States is:—

1. In breech loading ordnance, the combination of a single rigid cover for inclosing the whole of the breech mechanism and the firing mechanism and means for detachably connecting said cover in a watertight manner on the breech end of the gun.

2. In breech loading ordnance, the combination of a shoulder on the gun, a single rigid cover for inclosing the whole of the breech mechanism and the firing mechanism and means for holding said cover against said shoulder in a watertight manner.

3. In breech loading ordnance, the combination of a shoulder on the gun, a cover for inclosing the breech mechanism, a ring rotatably carried by said cover and means whereby angular movement of said ring presses said cover against said shoulder in a watertight manner.

4. In breech loading ordnance, the combination of a shoulder on the gun, a cover for inclosing the breech mechanism, a ring rotatably carried by said cover, and a bayo-

net joint connection between said ring and the breech end of the gun and serving when said ring is displaced to press the cover against the shoulder in a watertight manner.

5. In breech loading ordnance, the combination of a shoulder on the gun, a cover for inclosing the breech mechanism, a ring rotatably carried by said cover for pressing the cover in a watertight manner against said shoulder and means for exerting a powerful initial unlocking movement on said ring.

6. In breech loading ordnance, the combination of a shoulder on the gun, a cover for inclosing the breech mechanism, a ring rotatably carried by said cover for pressing the cover in a watertight manner against said shoulder, a projection on the gun and a screw threaded member interposed between said projection and the ring.

In testimony whereof we affix our signatures in the presence of two witnesses.

ARTHUR TREVOR DAWSON.
GEORGE THOMAS BUCKHAM.
